UNITED STATES PATENT OFFICE.

JOHN G. HARDY, OF PROVIDENCE, RHODE ISLAND, ASSIGNOR TO THE W. J. FEELEY CO.,
OF PROVIDENCE, RHODE ISLAND, A CORPORATION OF RHODE ISLAND.

DESIGN FOR A BADGE OR SIMILAR ARTICLE.

40,822.

Specification for Design.

Patented Aug. 16, 1910.

Application filed June 17, 1910. Serial No. 567,534. Term of patent 14 years.

To all whom it may concern:

Be it known that I, JOHN G. HARDY, a citizen of the United States, and a resident of Providence, in the county of Providence and State of Rhode Island, have invented a new, original, and ornamental Design for a Badge or Similar Article, reference being had to the accompanying drawing.

The figure is a face view, showing my design.

I claim—

The ornamental design for a badge or similar article, as shown.

JOHN G. HARDY.
